STRING MUSICAL INSTRUMENT

Raye Coplan, Jamaica, N. Y.

Application July 5, 1955, Serial No. 36,812

Term of patent 3½ years

(Cl. D56—9)

Fig. 1 is a front elevational view of a string musical instrument, showing my new design.

Fig. 2 is a side elevational view.

The side opposite that shown in Fig. 1 is substantially plain.

I claim:

The ornamental design for a string musical instrument, substantially as shown and described.
